UNITED STATES PATENT OFFICE.

WILLIAM F. BEATTY, OF CINCINNATI, OHIO.

WATER TRANSPORT OR FERRY FOR AUTOMOBILES AND OTHER SELF-PROPELLED VEHICLES.

Application filed July 7, 1921. Serial No. 483,068.

To all whom it may concern:

Be it known that I, WILLIAM F. BEATTY, a citizen of the United States, and a resident of Cincinnati, in the county of Hamilton and State of Ohio, have invented certain new and useful Improvements in Water Transports or Ferries for Automobiles and Other Self-Propelled Vehicles, of which the following is a specification.

10 This invention relates to water transports, ferries, or barges having no motive-power of their own but are adapted to be temporarily installed with portable, motor or electric driven land automobiles or the like that 15 are on the way, as it were, or in transit, so that freight or passengers can be carried or transported onwardly and forwardly without unloading same from the auto-truck between its initial point of receipt and loading 20 and its unloading destination that must be reached by crossing land and water alike, regardless of bridges, engine-propelled ferries, or fords at regular crossings, or at unfrequented crossings that might tend to 25 shorten the journey or make the trip of the truck shorter and otherwise more conveniently and economically accomplished. The object herein is intended to use the invention for short hauls very largely, owing to 30 the already well-known and established fact that the auto or motor truck is a time, money and labor saver, and that, when once loaded, its driver travels or advances as usual over land until he reaches a water-course or a 35 body of water, of greater or less depth, that must be crossed, then he drives the auto-truck on the motorless barge, provided herein and covered hereby, at any regular landing-place, or at an improvised one, as the 40 case may be, draws in the barge fastening lines or ropes and connects or couples his truck up with the paddle-wheels or suitable propellers on the barge so that said paddle-wheels or propellers can be operated or put 45 into motion by the engine-power of the truck, and rudders used at the opposite ends of the barge or water-craft whereby it can be steered by means of the steering-gear of the truck just as though the latter were being used and operated on land, and, on arriving at the desired landing-place across 50 the stream or body of water, or along the shore where a landing is provided or can be made, the barge is adapted to be suitably anchored, or otherwise held or lashed to the

shore, so that the truck can proceed on its way overland again or discharged or unloaded at that point if that be its destination, and being then ready for the return-trip with a reload.

Another object is to allow the truckman to drive onto the barge and drive from it without necessity of turning the barge around, it being furnished with guiding-rudders at its opposite ends, as before stated, and such rudders being connected with the steering-gear of the truck so that either one can be independently operated from either end of the said barge, no matter which way it may be headed.

An important object of the invention herein is the adaptability to use the steering-gear of the auto-truck the same on land and water, and the conversion of the portable automobile land-power into barge-moving water-power in a moment's time.

Another quite important object of the invention is to provide an auto-truck-propelled transporting barge, ferry, or barge, for freight and pleasure vehicles alike, that can be used to great advantage on still water as well as on running water or flowing rivers or streams, and without it being necessary to install a motor on the said water-craft. Such object would easily include under it the use of the transport or barge herein for military purposes and for floods, and more especially for shallow water, across marshes and the like, and, also, where bridges are down and being repaired. It can be used to great advantage in traversing canals and like inland waterways, to go singly, or to pull or to push one or more trailers, floats, lighters, or barges, that have no power of their own thereon, and to thereby accommodate and carry large quantities of freight and numbers of passengers, all with but the power of a single auto or electric truck.

Still another advantage gained in the use of the auto-truck on a barge or float is that detours can be readily made thereby when roads are impassable or in bad condition, saving on wheel tires during such float transportation and other wear and tear on the auto-truck outside of the use of the steering-gear and its engine. Quite another advantage is gained in the use of the auto-truck on the barge by saving the dismounting of the auto driver from his ma-

chine, as he can remain thereon and go ahead to drive it and operate its steering-mechanism the same as on land. Besides, power is saved when running downstream, 5 and, to go upstream, instead of going direct against the current, tacking back and forth across the stream may be resorted to, similar to sailing against the wind either up or down stream. Besides, roads themselves are 10 largely saved in moving heavy loads of freight on auto-trucks that are mounted and operated on transport barges and floats as herein provided.

In the accompanying two sheets of drawings—

Figure 1 is a longitudinal elevation showing the side of the auto-carrying barge or transport herein, and including an auto-truck in position thereon, headed to the left 20 in the view, the same direction as that of the barge; Fig. 2, a transverse section taken on an axial-line of the wheel-propellers to the right, in Fig. 1, but omitting the auto-truck; Fig. 3, a detail perspective view of 25 one of the compensating swivel or turn-table blocks used to accommodate the fore or guiding wheels of the auto-truck when it is on the transporting-barge and adapted to be connected with the rudder-operating 30 mechanism on the barge; Fig. 4, a plan view of Fig. 1, but, also, omitting the auto-truck; and Fig. 5, a detail elevation of the 35 emergency hand-propelling mechanism used on the barge for emergency movement or landing of the transfer-barge, especially when no auto-truck is present on its deck, or as otherwise desired; and Fig. 6, a detail 40 inverted plan view of the clutch used in the emergency screw-propeller operating-device shown in Figs. 1, 2 and 4.

A indicates on ordinary engineless barge, ferry, or float, having side-walls B, end-walls C, bottom D and deck or platform E, the said end-walls sloping or retreating inwardly, as shown in Fig. 1 and as customary in such flat-boat or flat-bottomed structures of the barge or float type.

F indicates an ordinary automobile-truck used for freight or merchandise, or for general transportation or passenger-carrying 50 purposes, and having the usual fore-wheels G, hind-wheels H and the customary steering-wheel I.

7 indicates each one of four side wheels 55 or propellers, mounted in transversely-aligned pairs near the opposite ends of the barge and supported on the outer ends of the short shafts 8 that journal in boxes 9 that are provided in the side-walls B, as 60 best shown in Fig. 2.

10, 10 indicate a spaced pair of bearing-boxes each one being provided at the lower end of a pendent-bracket 11, the latter being suitably secured to the bottom of the 65 deck or platform E of the transport-barge,

and a parallel shaft 12 is arranged above each of the shafts 8, beneath the platform, to carry a transverse corrugated or rubber-faced roller 13 located in an opening 14 just below the level of the underface of the platform, all as best shown in Fig. 2. A companion corrugated or rubber-faced roller 15 horizontally-parallels the roller 13 in each of the openings 14 and is carried by a shaft 12^a similar to the shaft 12 and likewise 75 journaled in the bracket 11. The inner ends of the corrugated-roller shafts journal in brackets 16 secured to the underside of the platform, also as best shown in Fig. 2. Companion spur-gears 17 and 18, that do 80 not intermesh, are mounted on the corrugated-roller shafts, adjacent the inner faces of the side-walls B of the barge, and a third spur-gear 19 is mounted on the short-shaft 8 of each side-propeller wheel for meshing 85 with the said several pairs of companion spur-gears 17 and 18, and the side-propeller wheels of the barge may be operated independent of each other, for making short turns or the like, by means of hand-lever 90 actuated clutch-devices 20, also as best shown in Fig. 2. When the auto-truck is in place on the deck or platform of the barge its rear or driving wheels H rest in the hollow or crotch between the companion pairs 95 of corrugated rollers 13, 15, the latter not touching each other and both being thus actuated in the same direction and causing the same direction of rotation to the companion spur-gears 17 and 18 that combine 100 their power in their meshing-contact with the spur-gear 19 on each side-propeller wheel shaft 8 to drive it by means of the power derived from the engine of the auto-truck.

The treads of the rear auto-truck wheels drop into the openings 14 of the platform which they clear, so that they can revolve free from contact with the platform, and to properly support the auto-truck at its rear-end free from contact with the platform and so that the said rear-wheels can convert or transmit their power to companion sets of corrugated or rubber-faced rollers 13 and 15 to drive either pair, or either one of such 110 pair, of side-wheels for propelling the transfer-barge or transportation-float in the direction desired. The speed of the barge is, of course, controlled or regulated by the operator in the auto-truck the same as that of 115 the latter when moving on land, and the stopping and starting of the barge is controlled from the same source.

In steering the barge, the fore-wheels of the auto-truck are adapted to rest in open, 125 oval-shape shoes or boxes 21 that rest and turn in circular openings 22^a made in longitudinally-slidable blocks 22 that engage elongated openings 22^b in the platform or deck E between the four rectangular roller- 130

openings 14 and the opposite ends of the said platform as best shown in Figs. 1 and 4, and to allow for different-spaced fore and rear wheels of the truck taken on the barge. Roller or ball bearings 23, best seen in Fig. 3 are preferred in the circular bottom or turn-table 24 of each shoe-support 21 in order to facilitate the ready adjustment of the shoe-supports to suit the position of the 10 said fore-wheels of the truck on the barge platform when the truck is being run into such position on the platform ready for the advance movement of the barge in the desired direction, and, also, for the ready 15 rotation of the turn-tables when the fore-wheels of the truck are in place thereon and adapted to clear the surface of the platform on rotating the steering-wheel L for swiveling the said fore-wheels while the truck is 20 on the deck of the barge and to direct or guide the latter through the action of rudders 25 preferably at both ends of the barge and that are controlled by means of the several cables or ropes 26 and 27, such cables 25 being counterparts of each other and made in like lengths whose opposite ends are each connected with an eye 28 (Fig. 3) at one end of one of the side-members or upright-jaws of one of the said open shoes or boxes 30 21 at one side of the platform and passed over a pair of idlers 30, 30, at one end of the platform; then passed mid-length over grooved pulleys 29, (dotted in Figs. 1 and 4); and thence crossed beneath the center of 35 the platform and with the other end of the cable connected with the eye 28 of the companion open shoe or box 21 alined therewith at the same end of the barge as the first-named shoe 21. The opposite ends of the 40 said cables 26 and 27 pass outward or upward through holes 31 made in the platform so as to reach the upturned-eyes 28 on the shoes that lie close to said holes. (See Fig. 4.) Idlers 32 are mounted beneath the 45 holes 31 for properly directing the cables to the eyes 28 without undue frictional-contact with the platform.

A clutch-device 33 (Fig. 6) is provided beneath the companion pairs of rollers 13 and 50 15 for connection with the companion transmissions of a pinion-and-shaft gear 33^a (dotted in Fig. 4) for using the screw-propellers 34 independent of each other, to couple with the roller devices and thereby accelerate the movement of the transport-barge 55 in transit. The clutches are each provided with an actuating-arm 35 (Fig. 6) having an eye 36 adapted to receive the end of a pull-rope (not shown) leading to any suitable source convenient to the operator of the barge who may be the auto-truck driver himself, and which is ordinarily intended, or by an attendant of the barge.

Landing-bridges or drop-stagings 37 are 60 65 provided at both ends of the barge, (Figs. 1

and 4), and duly hinged in place so that they can be carried in upright position (to the left in Fig. 1) when the barge is in transit, and adjusted in lowered position (to the right in Fig. 1) when the barge is 70 ashore and ready to run the auto-truck thereupon and therefrom.

A spring-presser arm 38 is provided on each of the shoes 21 for the purpose of conveniently manipulating them when it is desired to properly guide the fore-wheels of the truck into place in the jaws of the shoes, or to permit the jaw, on which it is mounted, to be tilted and adjusted for different widths of tires. 75

To actuate the barge by hand in case of emergency, which is both possible and probable, especially when no truck is aboard and no other motive power is present, a hand-wheel 39 is arranged at the middle of each 80 of the two side-walls B, B, of the barge, and its shaft has a sprocket-wheel 40 thereon, together with a pendent-arm 41, the latter being adapted to swing on said shaft away from a perpendicular line for due adjustment in connection with a train of gear-and-sprocket devices J and K at both sides of a sprocket-wheel L that is mounted at the lower end of the said pendent-arm 41 and whereby the transversely-alined pairs of 85 paddle-wheels are actuated at either end of the barge, and in either direction, so as to suit the direction of movement of the barge. The adjustment of the said pendent-arm 41 is effected by swinging it on its axis to the 90 right or left, as the case may be, to suit the pair of paddle-wheels that are to be used, and said pendent-arm is held in adjusted position by means of the projecting slotted-arm 42 that is secured in place on the inner 95 face of the vertical-extensions M of the side-walls B of the barge by means of set-screws or bolts 43. The two trains J and K mentioned (see Fig. 5) are suitably coupled with said screw-propeller shaft 44^a for rotating 100 the latter when desired, so that either one of said screw-propellers 34 can be rotated by turning either one of the hand-wheels 39 at the sides of the platform. The shaft 105 44^a journals at its opposite ends in the bearing-boxes 10, 10, at the lower ends of the pendent brackets 11, 11, as best seen in Fig. 2.

Fenders 45, shown in dotted lines in Fig. 4, are provided over the paddle-wheels for 110 115 their usual protective purposes.

I claim:—

1. In an auto-driven water-craft for transporting and ferrying automobiles and other self-driven vehicles, the combination of a 120 barge, float, or ferry having a deck or platform adapted to directly receive the said self-driven vehicle from either end thereof and that is to be transported, or moved on running or on still water on the way to its

destination, embarking and debarking means on said platform at opposite ends thereof, propeller-wheels on said water-craft, pairs of rollers mounted beneath the level of said 5 platform for each of said propeller-wheels at both ends of the craft and adapted to support the driving-wheels of the said self-driven vehicle out of contact with said platform when the vehicle has entered from 10 either end thereof, independent sets of gears connecting said sub-surfaced rollers with the said propeller-wheels at opposite ends of the craft, engine-means on said self-driven vehicle adapted to drive said propeller-wheels in either direction, swivel or turn-table shoe-supports mounted on said platform adjacent each pair of driving-wheel sub-surfaced supports and adapted to accommodate the fore-wheels of said vehicle 15 20 25 30 35 40 45 50 55 60 65 70 75 80 85 90 95 100

in either direction, steering-means on the said vehicle adapted to actuate the said swivel shoe-supports in steering the said craft, rudders at both ends of said craft, and cable-and-pulley devices or means interposed between the said swivel shoe-supports and the said rudders for guiding the craft, in either direction, through the medium of the said steering-means on said vehicle, substantially as shown and described.

2. In an auto-driven water-craft for receiving and transporting automobiles and other self-driven vehicles, the combination of a barge, float or other water-craft having a deck or platform adapted to directly receive and support the said vehicle from either end thereof and that is to be transported on water to its destination, embarking and debarking means at both ends of the said craft, propeller-wheels on said craft, pairs of assembled or associated rollers mounted on said platform beneath its upper level for actuating each of said propeller-wheels at opposite ends of the craft and adapted to otherwise support the driving-wheels of said vehicle out of contact with said platform, independent sets of coacting gears connecting the said sub-surfaced rollers with said propeller-wheels at opposite ends of the craft, engine-means on the vehicle adapted to drive said propeller-wheels on the craft in either direction, swivel shoe-supports on the platform adjacent the several driving-wheel sub-surfaced supports and adapted to accommodate the fore-wheels of the vehicle at opposite ends of the craft in either direction thereof, steering means on the vehicle adapted to actuate the said swivel shoe-supports in steering the craft, rudders at both ends of the craft, guiding means between the said swivel shoe-supports and the said rudders, and auxiliary or emergency manual-power driving means on the ferry for propelling or moving the craft when no self-propelled vehicle is present thereon or the vehicle is unusable though present thereon, substantially as shown and described.

WILLIAM F. BEATTY.
